PROPELLER FOR AIRCRAFT AND THE LIKE

René Lucien Lévy, Montrouge, France, assignor
to Société d' Inventions Aeronautiques et
Mécaniques S. I. A. M., Fribourg, Switzerland

Application May 16, 1935, Serial No. 21,856
In France June 5, 1934

3 Claims. (Cl. 170—162)

This invention relates to improvements in devices for regulating the pitch of propeller blades. The invention pertains more particularly to actuating systems for controlling the blades of variable pitch propellers, in which the variable aerodynamic pressure exerted on the blades as the latter rotate about the axis of the drive shaft, is continuously and automatically balanced by a back pressure furnished by a device which functions oleopneumatically.

The primary object is to improve devices of this general character by providing a propeller wherein the hub of said propeller is rotatably mounted on the drive shaft or an intermediate hub and is driven through an oleopneumatic coupling arranged between said propeller hub and said intermediate hub, which coupling yields in response to the torque transmitted to the propeller hub through said coupling. The relative rotary movement of the propeller hub and intermediate hub, acting through suitable devices to adjust the pitch of the blades in accordance with the relative rotary displacement thereof.

With the above and other objects in view which will appear as the description proceeds, the invention consists in the novel features hereinafter described in detail, illustrated in the accompanying drawing and more particularly pointed out in the appended claims.

In the drawing,

Fig. 1 is a front elevation, partly in section, of my improved device.

Fig. 2 is a vertical sectional view of the same.

Fig. 3 is a diagrammatic front elevation of a propeller.

Fig. 4 is an enlarged sectional view of a detail.

Fig. 5 is a vertical sectional view showing a modification of my invention.

Fig. 6 is a fragmentary detail in side elevation of a further modification.

Referring to the drawing in detail, P designates a pair of propeller blades rotatably mounted in a common blade carrier or hub A. The blades are adapted to rotate in said hub on the vertical axis X—Y, which axis also extends through the centres C of aerodynamic thrust exerted on the blades, as shown in Fig. 3. The hub A is rotatably mounted on an intermediate hub or member B which is keyed or otherwise secured to the front end of the main drive shaft M. The hub A will, of course, rotate about the axis Z—T of the drive shaft M.

An oleo-pneumatic coupling H, preferably formed integral with the intermediate hub B,

and connected with the propeller hub, acts to transmit the torque of the intermediate hub to the propeller hub. This coupling consists of a pair of diametrically opposed cylinders H arranged about the axis of the drive shaft and adapted to be filled with liquid, except for a space reserved initially for compressed air. A piston I is arranged within each of said cylinders, and each piston is connected to its respective propeller hub by means of a rod n, slidably engaging a bolt K projecting laterally from said hub.

When the engine is running and the drive shaft rotating in the direction of the arrow f (Fig. 3), the intermediate hub B will drive the propeller hub A through the agency of the oleo-pneumatic coupling. However, due to the aero-dynamic pressure exerted against the blades, the latter appear to turn through an angle α (off-set position, X¹—Y¹ of the axis X—Y), in the retrograde direction f', until the air pressure in the cylinders H of the oleo-pneumatic coupling balances the aero-dynamic pressure exerted on the centres of the thrust C on the blades.

In assuming this angle of lag α around the main axis Z—T, the intermediate hub B causes the blades P to turn on their longitudinal axis X—Y. To accomplish this purpose, the inner end p of each blade is provided with a finger g which extends through an opening l in the propeller hub A and engages a fork t carried by the intermediate hub B. The action of the forks t on the fingers g varies the turning of the blades on their longitudinal axis X—Y in a direction which corresponds with a reduction in the pitch of the propellers. Consequently, by this reduction in the pitch of the propellers, the aerodynamic thrust exerted against the blades and its effect upon the main drive shaft M is decreased. The speed of the engine increases therefore, until the aerodynamic pressure against the blades is balanced by the pressure of the oleo-pneumatic device.

The system constituted in this manner is therefore such that there corresponds with each value of the motive couple, a position of equilibrium of the aggregate of the blades P and hub A on the one hand, and of the oleo-pneumatic cylinders on the other, this position being determinable by the angle of lag α of the hub A and its blades. If said couple or the aerodynamic pressure exerted on the blades be large, and the speed of the aeroplane be small, the angle α will be of maximum value and consequently the pitch of the propeller will be at a minimum. If said couple be still large,

and the speed of the aeroplane increases the angle α will decrease, and consequently, the pitch of the blades will increase. If the motive couple remain constant, and the density of the air diminishes, the angle α will decrease and the pitch of the blades will increase. Finally, if the motive couple, the speed of the aeroplane, and the air density vary simultaneously, the angle α and, consequently the movement of the blades about their axis X-Y, will vary at the same time until the position of equilibrium is attained, which ensures the optimum value of propeller pitch compatible with the new running conditions.

A variable pitch propeller possessing the two fundamental characteristics defined above, therefore enables the pitch to adapt itself automatically in the most suitable manner, whatever may be the running conditions, speed or altitudes at which the aeroplane is flying. Its application to engines fitted with superchargers appears particularly indicated.

While other elastic couplings may be employed between the intermediate hub and the propeller hub, it will be noted that the oleo-pneumatic cylinder coupling herein defined offers several important advantages.

In the first place, this coupling affords the possibility of acting upon the variables, namely, the initial pressure of the air, and the clearance in the cylinders for the compressed air.

The propeller being adjusted to maximum pitch, the air pressure in the cylinders of the coupling H is adjusted initially so that the propeller will assume, at the determined point, the minimum pitch that is desired. If desired, suitable means (not shown) may be provided to permit the pilot to admit oil into the cylinders during flight when the engine races, in order to reduce the clearance in said cylinders while maintaining the same initial pressure of inflation.

Another advantage of the present type of coupling is that the oleo-pneumatic cylinders ensure hydraulic damping of the vibrations and shocks to which the propeller may be exposed as the result of changes in speed. To accomplish this result, I provide a diaphragm J in each cylinder, provided with a relatively small bore, which damps the movement of the pistons I in a well known manner.

Furthermore, oleo-pneumatic couplings of this type enable the pitch of the propeller to adjust itself automatically to the altitude. For example, as the aeroplane ascends, the compressed air in the cylinders of the coupling H retains its initial pressure, whereas the aerodynamic reaction on the blades diminishes, with the result that the pitch of the propeller will be automatically increased.

While the diaphragms J herein described and shown in Fig. 2 are particularly adapted to damp the vibrations and shocks to which the propeller may be exposed during the operation of the aeroplane, I prefer to employ the space e in the rear of the pistons I as a dashpot, to prevent shocks in the event of a more or less sudden drop in the engine speed. In such case, the piston rod passing through a stuffing box i, is articulated on the member K by means of a slot n or other connecting means allowing similar freedom of movement. The space e is connected with a casing 20 by a pipe 21. The head of the cylinder H is provided with a small bleed passage 23. A check valve 22 is provided in the casing adjacent the outlet end of the pipe 21 to permit the air from the space e to pass on out through the cas-

ing, but preventing the return of air to the space e through said casing.

It should also be mentioned that the inner end p of the blades P may be connected with the intermediate hub B by means other than the finger g and fork t described above. For example, as shown in Fig. 6, two bevel pinions, one of which (15) is integral with the inner end of the blade P, and the other (16) integral with the intermediate hub B may be employed to accomplish the same purpose, that is, vary the pitch of the propeller.

It will be understood that the system of automatic adjustment just described can be applied to any propulsive device for aeroplanes or the like, having a variable-pitch propeller.

The invention also comprises a simple device for assuring the continuous lubrication of the contact surfaces at the inner ends of the blades P of variable pitch propellers.

There are various types of thrust bearings, plain, ball-type, helicoidal ramp and the like, enabling the propeller blades to vary their pitch in relation to their longitudinal axis X-Y passing through the hub of the propeller. Whatever system may be employed, it is essential to insure thorough lubrication of the contact surfaces, in order that under the action of the efforts to which it is subjected, the propeller may assume the pitch corresponding with the optimum output of the propulsive system.

According to the present invention, a particularly advantageous method of lubrication consists in utilizing the action of centrifugal force to produce an effective forced lubrication of the inclines or sliding surfaces. In an embodiment represented in Fig. 5, where the blades turn on a helicoidal ramp, a cylinder 1, housed in the inner end p of the blades P and preferably coaxial with the rotational axis X-Y of the blade contains a piston 2, which is provided with a skirt or cup 3 and is continuously subjected to the action of a spring 4 tending to press it radially inwards. This piston 2 is composed of a heavy metal, for example, in the form of a lead block.

The upper compartment 5 of the cylinder 1, communicates, through passages 6, with various points on the helicoidal ramp 7, and may also communicate with the various members of the hub that are to be lubricated, especially the fingers actuating the movement of the blades.

When the propeller is at rest, oil is injected through a suitable passage 8, into the center of the hub from which, by way of the passage 9, it fills the compartment 5. On the engine being started, centrifugal force acting on the block 2 compresses the spring 4, the results being to force the oil into the hub and into the narrow passages 6 supplying the ramp or the thrust bearings of the blade, so that highly efficient forced lubrication is continuously assured.

I claim:

1. In a propelling mechanism, a driving shaft, an intermediate hub fixed to said shaft, a propeller hub rotatably mounted on said intermediate hub, propeller blades rotatably mounted in said propeller hub, a resilient coupling including pneumatic cylinders rigid with one of said hubs, and piston members arranged in said cylinders and connected to the other hub for transmitting the rotary motion of the driving shaft to said propeller blades, said resilient coupling responding during rotation of said shaft whereby an angular displacement occurs between the propeller 75

hub and said shaft, means connecting said intermediate hub with said blades for varying the pitch of said blades a definite relative value for each value of said angular displacement, and diaphragms in said cylinders having openings for retarding the movement of fluid in said cylinders.

5. In a propelling mechanism, a driving shaft, an intermediate hub fixed to said shaft, a propeller hub rotatably mounted on said intermediate hub, propeller blades rotatably mounted in said propeller hub, a resilient coupling including pneumatic cylinders rigid with one of said hubs, and piston members arranged in said cylinders and connected to the other hub for transmitting the rotary motion of the driving shaft to said propeller blades, said resilient coupling responding during rotation of said shaft whereby an angular displacement occurs between the propeller hub and said shaft, means connecting said intermediate hub with said blades for varying the pitch of said blades a definite relative value 10 for each value of said angular displacement, and means in said cylinders for restricting the movement of fluid therethrough, and dash pots connected with said cylinders for damping shocks incident to sudden decrease in the speed of rotation of the driving shaft.

15. In a propelling mechanism, a driving shaft, an intermediate hub fixed to said shaft, a propeller hub rotatably mounted on said intermediate hub, propeller blades rotatably mounted in said propeller hub, a resilient coupling including pneumatic cylinders rigid with one of said hubs, and piston members arranged in said cylinders and connected to the other hub for transmitting the rotary motion of the driving shaft to said propeller blades, said resilient coupling responding during rotation of said shaft whereby an angular displacement occurs between the propeller hub and said shaft, means connecting said intermediate hub with said blades for varying the pitch of said blades a definite relative value 15 for each value of said angular displacement, and means in said cylinders for restricting the movement of fluid therethrough, and dash pots connected with said cylinders for damping shocks incident to sudden decrease in the speed of rotation of the driving shaft.

20. In a propelling mechanism, a driving shaft, an intermediate hub fixed to said shaft, a propeller hub rotatably mounted on said intermediate hub, propeller blades rotatably mounted in said propeller hub, a resilient coupling including pneumatic cylinders rigid with one of said hubs, and piston members arranged in said cylinders and connected to the other hub for transmitting the rotary motion of the driving shaft to said propeller blades, said resilient coupling responding during rotation of said shaft whereby an angular displacement occurs between the propeller hub and said shaft, means connecting said intermediate hub with said blades for varying the pitch of said blades a definite relative value 20 for each value of said angular displacement, and means in said cylinders for restricting the movement of fluid therethrough, and dash pots connected with said cylinders for damping shocks incident to sudden decrease in the speed of rotation of the driving shaft.
